UNITED STATES PATENT OFFICE.

WILLIAM E. WINE, OF TOLEDO, OHIO, ASSIGNOR TO WINE RAILWAY APPLIANCE COMPANY, OF TOLEDO, OHIO, A CORPORATION OF OHIO.

BODY BOLSTER.

REISSUED

Original application filed May 6, 1927, Serial No. 146,977. Divided and this application filed November 21, 1927. Serial No. 234,740.

My invention relates to new and useful improvements in body bolsters and the present application is a division of the application filed by me on May 6, 1927, bearing 5 Serial No. 146,977, and entitled Freight cars.

One of the objects of the present invention is to provide a body bolster, composite in form and made up primarily of three main pieces, together with reinforcing plates and 10 gussets to provide an exceptionally strong bolster.

Another object of the invention is to provide a composite form of bolster that is designed to support and reinforce a slope sheet 15 which slope sheet is fully described and explained in the parent application.

Still another object of the invention is to provide a composite type of truck bolster, which bolster will accommodate Z-bars, which 20 Z-bars are located near the opposite ends of a freight car where the ends are slightly offset, this type of car being known as a "full capacity car."

Still another object of the invention is to 25 provide a bolster that will properly accommodate special types of side sills, which side sills are shown in a parent application and also forms the subject-matter of a divisional application about to be filed.

Still another object of the invention is to 30 provide a body bolster made up of a number of plates or parts and the parts so arranged and fastened together that the bolster will be exceptionally strong at points located directly over the side bearings when of course, 35 the bolster is in position in the car.

With these and other objects in view, the invention consists in certain new and novel arrangements and combination of parts as 40 will be hereinafter more fully described and pointed out in the claims.

Referring now to the drawings showing a preferred embodiment of the invention,

Fig. 1 is a view in elevation of the body bolster, parts of a car and slope sheet being 45 shown in cross section.

Fig. 2 is a sectional plan of the body bolster, a part of a car also being shown in section.

Fig. 3 is a side elevation of the center and 50 end sheets of the composite bolster, showing the bolster in its partly assembled position.

Fig. 4 is an enlarged transverse sectional view showing the construction of the bolster and the manner of supporting a slope sheet.

Fig. 5 shows a plan and side elevations of 55 a right-hand reinforcing plate.

Fig. 6 shows similar views of the reinforcing plate disposed directly opposite the plate shown in Fig. 5.

Fig. 7 is a fragmentary sectional view 60 taken on line 7—7 of Fig. 1.

Fig. 8 is a perspective of the braces shown in Fig. 7.

Referring now more particularly to the several views, and to Fig. 1 in particular, for 65 the moment, there is shown, the completed bolster 11 which is designed to support a slope sheet 34 of the car, this slope sheet forming no part of the present invention, although it is to be understood that different forms of 70 slope sheets might be equally as well supported by a bolster of this kind.

In this Fig. 1, there is also shown in section the end side plates 8 and two oppositely positioned Z-bars 10 located in the maximum 75 capacity cars near the opposite ends so that the end side plates may be set in, slightly, from the normal sides of the car, and at the same time allow for the provision of safety appliances, all of which, will be understood, 80 by those skilled and familiar with the art of freight cars.

Also shown in this Fig. 1 are two angles A, which parallel the opposite edges of the slope sheet and these angles are fully described in 85 the parent application. Likewise, small reinforcing plates 19 are shown connected to the upper ends of the Z-bars to brace the top rails 5 of the freight car and corner braces 7 may be noticed in Fig. 1. 90

Near the lower corner of the opposite ends of the bolster, will be noticed the side sills 15 and the angle bars 16 which are secured to the bolster but these side sills form the subject matter of a further divisional application. 95

The above short description of the side stakes, slope sheet, angles A, and the side sills, is set forth as the bolster is especially arranged and designed to accommodate these several parts, and the special construction of 100 the bolster will be more fully understood and appreciated if its cooperating parts are briefly set forth.

Referring now more specifically to the actual construction of the bolster, it will be 105 seen that it comprises, or is made up, primarily of three main pieces, to wit, a center plate 56, an end piece 57, and another end piece 58.

The center piece 56 consists of a steel plate, having the tapered edges 59 and 60, while the bottom edge 61 is provided with a flange 62 and the upper edge with another flange 63. 5 This flange 62 extends right over the center sill 64 shown in section in Fig. 1.

Referring now to the right-hand end piece 58, it will be seen that it comprises an irregularly-shaped plate having a slightly reduced corner 65 for the reception of the ends of a side sill 15, while at a short distance from this point, that is, from a point 66, the edge widens and extends downwardly to the corner 67 where it merges with the edge 68 10 of the plate, which edge then extends angularly upward to a point 69 where it again extends vertically.

The upper edge of this end piece 58 is provided with a flange 70 which registers when 20 in position, with the flange 63 of the plate 56. There is a slight offset in the flange 70, at the point 71 after which it continues to the point 72, where it is slightly tapered and merges with the right-hand end of the plate.

25 The other plate 57 is of a similar construction, but arranged to be oppositely positioned so that its flange 73 will register with the aforementioned flanges 63 and 70 of the other two plates. In a like manner, a small offset portion 74 is provided so that the space between these two offset portions 71—74 will accommodate a small plate 40 (see Figs. 1 and 4) which plate is riveted to a slope sheet 34 which will extend from the end of the car 30 down to the hopper.

The angle of the flanges 73, 63 and 70 may be clearly discerned in Fig. 4, they following the angle, of course, of the inclination of the slope sheet and the small reinforcing plate.

40 To properly tie the several plates 56, 57 and 58 of the bolster together, and to strengthen the bolster at a point over the center sill 64, and to also form special reinforcing means for the side bearings, I have provided two gussets or reinforcing plates 75 and 76, these being shown in position in Figs. 1 and 2. These plates are slightly different in contour so they will be described individually.

50 However, before describing the plates specifically, it is to be understood that there will be two plates of the form shown in Fig. 5, and two plates of the form shown in Fig. 6, and it will also be understood that the two plates of the form shown in Fig. 5, will consist of a right and left-hand plate as these extend on the one side of the center and end plates of the bolster, while two plates of the form shown in Fig. 6 will extend on the other side of this center end plate, and likewise the plates shown in Fig. 6 will be right and left-handed.

In other words, I have shown the right hand plate of each pair and there will be a left hand plate for each pair.

Referring to Fig. 5, it will be seen that the plate 75 has a sloping upper edge 77 while the lower edge 78 is inclined and provided with two offset portions 79 and 80. One edge of the plate is provided with the flange 81 which tapers off as it approaches the point 82 on the upper edge of the plate, while the opposite edge of the plate is provided with the flange 83 which is parallel throughout its length with the body of the plate. This gusset plate 75 is shown in position in Fig. 1 and it will be noticed that it laps over the adjacent edges of the plates 58 and 56 and is tightly riveted thereto, and its upper flange 77 is riveted to the flanges 63 and 70 of these two said plates. 80

The bottom edge of this plate 75 is also provided with the flange 78 and this flange with an offset portion 79 rests on the corner of the flange about the lower edge of the plate 58 while the offset portion 80 fits over the 85 flange of the beam of the center sill 64 as may be seen in Fig. 1.

A gusset plate 75^a (see Figs. 1 and 2) similar to plate 75, except that it is a left hand plate instead of a right hand one, is riveted to the plates 56 and 57, as may be clearly seen in Figure 1, these two plates 75 and 75^a together with the plate 56 enclose three sides of the center sill, while a bottom plate 86 extends entirely across the bolster 95 and under the center sill, which plate also ties the several parts firmly together.

Referring now to the gusset plate 76 which appears on the other side of the bolster from that just described, it will be noted that there 100 is no upper flange provided, the side flange 87 simply tapers upwardly and merges with the top edge of the plate.

One corner of this plate is offset as at 88 while the bottom edge tapers upwardly as at 105 89 and is offset again at 90. The small flange 91 extends around the side as seen in Fig. 6, and along the lower edge of the plate is also formed the flange 92, while flange, of course, has the offset portion corresponding to the 110 lower edge of the plate where the offsets 88 and 90 occur.

There will be a similar adjacent plate 76^a but in this instance the plate will be a left hand one, which may be clearly seen in Figure 115 2.

The lower flanges of all of these plates 75, 75^a, 76 and 76^a, will be riveted as at 93 to the sheet or bottom plate 86 as may be seen in Figures 2 and 4.

Referring now again to Figures 1, 7 and 8 for the moment, it will be seen that additional braces in the form of triangular plates or brackets 94 are riveted to the plates 75 and 76 and likewise it will be understood that there are two similar ones riveted to the plate 75^a and 76^a, so that there will be five thicknesses of metal on a line drawn through each of these gusset plates. In other words there will first be the bracket 94, a plate 75^a, an end 130

plate 57, a plate 76^a, and the further bracket 94. This construction will appear, of course, to the left of the bolster and also to the right of the bolster, as well, that is, on opposite 5 sides of the center sill. These brackets on their bottoms are riveted to the bottom flanges of the respective gusset plate 75 and 75^a and in the same manner the two brackets at the rear of the bolster will be riveted to the 10 plates 76 and 76^a also through the plate or strap 86. There is also an additional plate or support 95 as may be seen in Fig. 7, on which there will be riveted a wear plate 96. This wear plate 96 is the wear plate for the 15 side bearing, not shown, which will be mounted on the truck bolster.

Fig. 7 shows the manner in which the brackets are slightly offset on their bottom edges to accommodate the lower flanges of 20 the several plates 75, 75^a, 76 and 76^a.

From the foregoing it will be seen that I have produced a novel form of composite truck bolster which will accommodate the center sill, side sills, and Z-bars and is also 25 designed to lend support to the usual slope sheets that extend to the hoppers of the car.

Furthermore, it will be seen that the bolster consists primarily of three main sheets or 30 parts, to which are secured two pairs of right and left-hand plates, which several plates overlap the adjacent edges of the three primary plates. Besides these plates there are 35 brackets provided, so that there will be five thicknesses of metal directly over the wear plate of the side bearing.

It will also be seen that by forming a bolster in this manner, the several parts may be cut and stamped out of metal and readily assembled and riveted together, which assembly 40 may be easily performed in a shop designed to handle this class of work.

It will be understood that the numerous flanges and offset portions might be easily 45 changed to suit the particular conditions called for, and to fit other forms of center or side sills, or other forms of slope sheets, and the present illustration of these features is simply exemplary.

The bolster is one that is relatively light, 50 and at the same time has great strength and rigidity and will stand the hard usage and the heavy weight to which it is to be subjected.

Other changes might be made without departing from the spirit and scope of the invention.

Having thus described my invention, what I claim as new and desire to secure by Letters Patent is:

1. A bolster for a freight car comprising two similar end plates and a center plate, the end plates being oppositely arranged with respect to each other and four smaller plates arranged two on each side of the said bolster 65 to thereby tie the three major plates together.

2. A bolster of composite form consisting of a center and two end plates, two smaller plates arranged on one face of the bolster and the said smaller plates tying the end plates to the center plate and also tying the 70 oppositely arranged smaller plates to each other.

3. A bolster of composite form consisting of a central plate and two like but oppositely arranged end plates, the upper edges of all 75 of said plates being flanged, flanges around the outer and bottom edges of said plates and a plurality of smaller flanged plates tying the central and end plates together.

4. A bolster of composite form comprising 80 a central plate having an inclined flange along its upper edge and two end plates positioned respectively adjacent the said first mentioned plate and the said end plates having flanges extending around their three sides, 85 further reinforcing plates arranged on the opposite faces of said central and end plates and fitting between the upper and lower flanges of said plates and said last mentioned plates being riveted to the center and end 90 plates to thereby tie the several plates together.

5. A body bolster comprising a centrally positioned plate and two oppositely arranged end plates, two sets of reinforcing plates arranged on the opposite faces of said first 95 mentioned plates and each set over-lapping the center and one of said end plates, flanges on said first mentioned plates and flanges on said reinforcing plates and the flanges of the 100 reinforcing plates fitting within the flanges of the center and end plates.

6. A body bolster comprising a center plate and a right and left hand end plate, a pair of reinforcing plates over-lapping the adjacent 105 ends of the center and respective end plates, the center and end plates provided with a sloping flange along their upper edges, the reinforcing plates having similar flanges along their upper edges and riveted to the 110 first mentioned flanges and a strap extending along the entire lower edges of the end plates and the reinforcing plates.

7. A composite bolster formed of three main plates and sloping at its bottom edge 115 from its center upwardly toward its ends, reinforcing plates on the opposite faces of said bolster tying the three main plates together and also tying the reinforcing plates respectively to each other.

8. A body bolster comprising a centrally located plate and two oppositely arranged end plates, each of said end plates sloping from its inner portion upwardly to its outer edge, each of said end plates provided with 125 a flange around its upper edge, end, and lower edge, sets of reinforcing plates spaced from each other and tying the centrally arranged plate and the end plates together, the lower edge of said reinforcing plates provided with 130

flanges and fitting within the lower flanges of said end plates and additional brackets secured on the opposite faces of both of said sets of reinforcing plates.

5. 9. A composite bolster comprising a center plate 56, the end plates 57 and 58, the reinforcing plates 75 and 76, and the like plates 75^a and 76^a and the additional brackets 94.

10. 10. A composite bolster comprising the plates 56, 57 and 58, having the respective upper flanges 63, 73, 70, reinforcing plates 75, 75^a, 76, 76^a, brackets 94 and the lower strap 86.

11. 11. A bolster having wear plates for side bearings, the bolster formed of three main plates, reinforcing plates arranged on the opposite faces of said bolster plates and overlapping the adjacent edges of said main plates, brackets, also secured to said reinforcing plates to provide five thicknesses of

metal in cross section directly above the said wear plates.

12. 12. A bolster of composite form consisting of three main plates and two sets of reinforcing plates, each set having one plate with a straight edge at its top and the other plate with a sloping edge, the side edges of said plates tapering towards the top of the respective plates.

13. 13. A bolster of composite form consisting of a center and two end plates, two sets of reinforcing plates, each set being riveted to the front and rear faces of the said main plates of the bolster, one plate of each of the reinforcing plates having a sloping upper edge and the other of said plates of both sets extending in a horizontal plane.

In testimony whereof I affix my signature.

WILLIAM E. WINE.
